Paul M. De Angelis, Wauwatosa, Wis.

Application June 4, 1954, Serial No. 30,801

Term of patent 7 years

(Cl. D35—2)

To all whom it may concern:

Be it known that I, Paul M. De Angelis, a citizen of the United States, residing at Wauwatosa, in the county of Milwaukee and State of Wisconsin, have invented a new, original, and ornamental Design for a Combined Tong and Spade, of which the following is a description, reference being had to the accompanying drawing forming a part thereof.

In the drawing:

Fig. 1 is a plan view of a combined tong and spade embodying my new design;

Fig. 2 is a side elevation of the combined tong and spade;

Fig. 3 is a section through the combined tong and spade, taken along the line 3—3 of Fig. 2; and

Fig. 4 is a perspective view of the combined tong and spade, drawn to reduced scale.

I claim:

The ornamental design for a combined tong and spade, substantially as shown.
